UNITED STATES PATENT OFFICE.

RAYMOND T. PIERCE, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRICAL MEASURING INSTRUMENT.

Application filed February 3, 1923. Serial No. 616,736.

My invention relates to electrical measuring instruments and particularly to the movable elements thereof.

One object of my invention is to provide 5 a device of the above indicated character that shall be simple and durable in construction, economical to manufacture and effective in its operation.

Another object of my invention is to provide 10 a simple means for clamping an instrument coil to a shaft and for retaining the shape of the coil.

Another object of the invention is to provide 15 a movable element for an electrical measuring instrument that shall embody a novel combination conducting lead and spring-holding structure.

A further object of my invention is to provide 20 a damping vane structure for an electrical meter that shall be of such construction and so frictionally held in position as to greatly facilitate its assembly and to render the same durable in construction and effective in operation.

25 In practicing my invention, I provide a coil, preferably of substantially oval shape, that is transversely divided to admit a meter shaft therethrough. Clamping members are provided at the two points of intersection of the shaft with the coil, from one of which clamps a novel combination conducting-lead and spring-holding device extends for a distance along the shaft to a position adjacent to a damping vane structure of novel construction that is frictionally mounted on the shaft.

30 Figure 1 of the accompanying drawing is a top plan view of a meter element embodying my invention.

35 Fig. 2 is a side elevational view partially in section of the device shown in Fig. 1.

Fig. 3 is a longitudinal sectional view of the device taken at right angles to Fig. 2, and

40 Figs. 4 and 5 are detail plan views of members for holding damping vanes shown in Figs. 2 and 3, in position.

The device of my invention comprises, in general a meter shaft 1, a coil 2, clamping members 3 and 4, a combination conducting-lead and spring-holding device 5 and a damping-vane structure 6.

45 The coil 2 is preferably wound to be of substantially oval shape and is transversely divided, as indicated by an opening 7, to admit the shaft 1 therethrough.

The clamp 3 is preferably constructed of flat strap metal having a central opening which surrounds the shaft 1 and outer end portions 8 which are bent downwardly and inwardly around the outer lateral edges of 60 the coil 2. A strip of sheet insulating material 9 may be placed between the clamp 3 and the coil 2. The above construction serves not only to firmly secure the coil to the shaft 1, but also serves to prevent the spreading or 65 separating of the turns of the coil 2.

The clamp 4, somewhat similar to the clamp 3, is similarly provided with ends 10 which surround the coil 2 over a sheet of insulating material 11, and is further provided with a sleeve portion 12 into which a cylindrical tube of insulating material 14, 70 constituting a portion of the device 5, extends.

The device 5 further comprises a conducting strip 15 having laterally extending portions 16 and 17 adjacent to its upper and lower ends, respectively, that are bent into holding relation around tube 14. The portion 16 and a portion of the tube 14 extend 75 into the sleeve 12 by which they are clamped in telescopic relation around the shaft 1. The strip 15 is also provided with a portion 18 of substantially hook shape to which the end of a spiral spring (not shown) may be 80 suitably attached, as by clamping or soldering.

The damping vane structure 6 comprises a pair of diametrically opposite vanes 19 having reinforcing ridges 20 and laterally 85 extending reinforcing perimetral flanges 21, portions of which extend beyond the inner ends of the vanes proper to provide holding portions 22 and 23.

The portions 22 are frictionally wedged 90 or clamped between an annular member or cylinder 24 and portions 25, of reduced diameter, of a bushing 26 that is preferably press fitted on the shaft 1. The portions 23 are frictionally clamped or held in position 95 between a portion of the cylinder 24 and portions 27, of reduced diameter, of another cylinder 28 that is telescopically related to the cylinder 24.

The arrangement of parts provides a novel 100 meter element that is compact, neat, simple and durable in construction and economical to manufacture, that facilitates the assembly of the instrument and that is effective in its 105 operation.

While I have shown and described a particular form of my invention, changes may be effected therein without departing from the spirit and scope thereof, as set forth in the appended claims.

I claim as my invention:—

1. An electrical measuring instrument comprising a coil having a portion of substantially flat-strap formation, a sheet-metal element of substantially flat-strap formation disposed transversely to said coil portion in parallel-plane relation thereto, and a shaft extending normal to, and through, said coil portion and said element, said element having outer end portions bent around opposite edges of said coil portion and being adapted to secure the coil to the shaft.
2. In an electrical measuring instrument, the combination with a shaft and a coil mounted thereon, of a body of insulating material extending from the coil for a distance along the shaft and a conducting lead extending along said body said lead having an integral portion for mounting the same in position.
3. In an electrical measuring instrument, the combination with a shaft and a coil mounted thereon, of a body of insulating material extending from the coil for a distance along the shaft and a conducting lead extending along said body having an integral portion for mounting the same in position and a spring-receiving portion.
4. In an electrical measuring instrument, the combination with a shaft and a coil mounted thereon, of a body of insulating material extending from the coil for a distance along the shaft and a conducting lead extending along said body and having a laterally-projecting portion for holding the lead to said insulating body.
5. In an electrical measuring instrument, the combination with a shaft and a coil

mounted thereon, of an insulating tube surrounding and extending along the shaft for a distance from the coil and a conducting lead for the coil extending along and having a portion extending around the outer surface of said tube.

6. In an electrical measuring instrument, the combination with a shaft and a coil mounted thereon, of an insulating tube surrounding and extending along the shaft for a distance from the coil and a conducting lead for the coil extending along and having a transverse portion bent around a portion of the tube.

7. In an electrical measuring instrument, the combination with a shaft and a coil mounted thereon, of an insulating tube surrounding and extending along the shaft for a distance from the coil and a conducting lead for the coil extending along and having a transverse portion bent around a portion of the tube, said lead also having a portion for clamping operative relation to a spring.

8. In an electrical measuring instrument, the combination with a shaft, of a damping-vane structure comprising a bushing on the shaft, a cylinder surrounding the bushing and a vane member having portions clamped between the bushing and the cylinder.

9. In an electrical measuring instrument, the combination with a shaft, of a damping-vane structure comprising a bushing on the shaft, a pair of telescopically related cylinders, a portion of one of which surrounds the bushing, and a vane member having a portion held in position between the bushing and said cylinder portion and a portion held in position between said cylinders.

In testimony whereof, I have hereunto subscribed my name this 26th day of January, 1923.

RAYMOND T. PIERCE.
